THOMAS W. BUCK HOSIERY CO., OF PHILADELPHIA, PENNSYLVANIA, A CORPORATION OF PENNSYLVANIA

FABRIC TAKE-UP FOR KNITTING MACHINES

Application filed May 21, 1930. Serial No. 454,259.

This invention relates to fabric take-ups for knitting machines, particularly for flat knitting machines, known as "footers", such as are used in the production of full fashioned hosiery.

In manufacturing full fashioned hosiery, the stocking leg blanks knit on "leggers" are transferred to the "footers" for completion of the foot portions of the stockings as integral continuations, i. e., the terminal courses of the instep portions of the leg blanks and the inside selvage edges of the heel tabs are aligned and impaled on the needles of the "footers", and the stocking blanks connected to the "take-ups" of the machines. Each such take-up ordinarily consists of a roller, a pull strap adapted to be wrapped on the roller as the fabric is being knitted, and a draw bar designed for direct attachment to the stocking leg blank. The usual form of draw bar is provided with end hooks for engaging the heel tab portions of the leg blanks, and intermediate hooks for similarly engaging the instep portions of the blanks between the heel tabs. As a rule, the insteps of the stocking blanks are knit from delicate yarns of very fine gage as compared to the heel tabs, and, due to uneven localized strains induced by the intermediate hooks of the draw bars heretofore, the fabric was unduly stretched and distorted, and very often torn with resultant production of seconds which had to be disposed of at a loss.

The present invention has for its object to overcome the several disadvantages just pointed out. This desideratum I aim to attain through provision of a draw bar with means to clampingly engage the intermediate or instep portions of the leg blanks and thus preclude the possibility of injury to the fabric while maintaining the same evenly tensioned across the width of the blanks.

In the drawings, Fig. I is a fragmentary sectional view of a stocking footer equipped with my novel draw bar.

Fig. II is a plan view of the bar.

Fig. III is an edge view of the same; and

Fig. IV is a perspective view corresponding to Fig. I and showing more clearly the man-

ner in which the draw bar of my invention is used.

With more detailed reference to these illustrations, the numerals 10 and 11 designate respectively, the needless and the sinkers of the knitting machine which cooperate with them in producing fabric in the known way, and 12 indicates the take-up roller, which, as usual, is fitted with a strap 13, whereto, as shown, is attached the draw bar 14 with which the present invention is concerned. The draw bar 14, per se, has the customary configuration, and at its ends is provided with the usual hooks 15 to engage the heel tabs H of the stocking blanks B as shown in Fig. IV. From Figs. II and III it will be noted that the draw bar 14 is formed near one end with an upstanding bearing projection 16 which affords pivotal support to a finger-like lengthwise-extending member 17 for clamping the stocking blank against the top of the bar as hereinafter more fully explained. The rounded shank portion 18 of this finger-like clamp member 17 is sheathed with rubber or other yielding material as at 19 to preclude injury to the fabric, and said shank portion has its free end turned up as at 20 to facilitate placement of the fabric thereunder. Outward beyond the point of pivotal connection with the bearing 16, the clamp member 17 is provided with a finger tab 21; and a spring 22 interposed between said tab and the bar 14 tends to maintain the rubber covered shank 18 of said clamp member firmly pressed against the fabric as shown in Fig. IV.

The use of my novel draw bar is as follows: Assuming that a stocking blank B has been transferred to the needles 10 of the machine in the known manner, the finger tab 21 of the clamp member 17 is depressed in opposition to the spring 22, and the shank 18 of said member thereby raised to open position whereupon the draw bar 14 is applied cross-wise of the instep portion of the transferred leg blank B (Fig. IV). After proper positioning of the bar, the clamp member 17 is released, and, under the pressure of the spring 22, its sheathed shank 18 is pressed firmly cross wise over the instep portion of

the stocking blank on the bar. With the draw bar now attached to the fabric, the heel tabs H (Fig. IV) are pulled over the end hooks 15 whereupon the machine is started 8 to proceed with the knitting of the foot portion of the stocking as an integral prolongation of the transferred leg blank in a well known way.

From the foregoing it is evident that the 10 draw bar of my invention is simple in construction, inexpensive to manufacture, and easily applied to the stocking blanks. The substitution, as herein explained, of a clamp member in lieu of the intermediate hooks 15 usually employed on ordinary draw bars, precludes tearing of the fabric, and, moreover, insures firm gripping of the instep portion 20 of the stocking blank and maintenance of uniform tension at all points crosswise of the fabric.

Having thus described my invention, I claim:

1. A draw bar for fabric take-ups of flat knitting machines having a pivotally-25 attached spring-urged lengthwise-extending member for clamping the fabric to the bar.

2. A draw bar for fabric take-ups of flat knitting machines having a spring-urged finger-like lengthwise-extending member for 30 clamping the fabric to the bar, said member being pivotally attached to the bar at one end only with capacity for being swung to open position to facilitate application of the bar to the fabric.

3. A draw bar for fabric take-ups of flat knitting machines having a spring-urged finger-like lengthwise-extending member for clamping the fabric to the bar, said member being pivotally attached to the bar at one 40 end only and being provided with a finger tab beyond its pivotal connection whereby it may be swung to open position to facilitate application of the bar to the fabric.

4. A draw bar for fabric take-ups of flat knitting machines having a spring-urged finger-like lengthwise-extending member sheathed with yielding covering for clamping the fabric to the bar, said member being pivotally attached to the bar at one end only 50 with capacity for being swung to open position to facilitate application of the bar to the fabric.

5. A draw bar for fabric take-ups of flat stocking footers, having end hooks for engaging the heel tabs of transferred stocking blanks, and a pivotally-attached, spring-urged lengthwise extending member intermediate the end hooks for clamping the instep portion of the leg blank to the bar.

60 In testimony whereof, I have hereunto signed my name at Philadelphia, Pennsylvania, this 15th day of May, 1930.

FREDERICK H. FULMER, Jr.
